UNITED STATES PATENT OFFICE

1,999,202

HAULAGE MECHANISM

Robert C. Osgeod, Claremont, N. H., assignor to
Sullivan Machinery Company, a corporation
of Massachusetts

Application December 30, 1932, Serial No. 649,589

10 Claims. (Cl. 254—187)

My invention relates to haulage mechanisms, and particularly to haulage mechanisms adapted to provide a plurality of speeds and having means for automatically effecting a change from one winding speed to another.

During the mining of coal it is common to prevent subsidence of the roof by using mine props to support the roof, such props being either made of timber or of steel or the like. After the coal has been removed from a considerable area it may be desirable to allow the roof to come in, and when this is to be done a considerable saving can be effected if the props can be saved, for these may be used over in other places. In removing the props they are "pulled", and because of the fact that they are under very heavy stress, due to the weight of the roof acting upon them, it takes a very considerable force to release them. It is necessary, particularly in some places where the roof is "tender", to provide means for quickly withdrawing the prop from the position in which it has stood in order that it may not be pinched by the descending roof and thereby lost. A pull of several thousand pounds is necessary when applied at one end of the prop to dislodge it, but a very much lower pull is necessary to move it after it has been released, but the reduced pull must be at such a rate that the prop will be gotten away before the roof can fall upon it. To make sure of getting out the prop, it is highly desirable that there be provided automatic means for effecting the very rapid application of the quicker speed of withdrawal of the prop after it falls.

It is an object of the present invention to provide an improved haulage mechanism. It is another and more specific object of the invention to provide an improved haulage mechanism for use in pulling props. It is a still further object of the invention to provide an improved haulage mechanism providing a plurality of haulage speeds with means for effecting an automatic change in speed upon a predetermined variation in load. It is a still further object of my invention to provide an improved haulage mechanism having a plurality of concurrently-energized drum-driving trains, and having incorporated therein means for rendering the one train or the other effective, dependent upon the resistance to drum rotation. Other objects and advantages of my invention will hereinafter more fully appear.

In the accompanying drawing, in which, for purposes of illustration, one illustrative embodiment of my invention is disclosed:

Fig. 1 is a plan view of a hoisting mechanism

in which the illustrative embodiment of my invention is incorporated;

Fig. 2 is a horizontal section through the mechanism of Fig. 1;

Fig. 3 is a plan view of the illustrative embodiment of my invention in use in the pulling of the prop;

Fig. 4 is a side elevation of an operation similar to that shown in Fig. 3.

Referring to the drawing, it will be observed that upon a suitable base or skid mounting there are provided a pair of upright bracket members 2 and 3 held by machine screws or the like, 4, to the skid member 1; near one end of the skid member and beyond the bracket members 2 and 3, there is arranged a driving motor 5 having a controller, and if desired a reverse mechanism, all housed within a casing 6. Near the opposite end of the skid member and journaled in bearings within the upstanding bracket members 2, 3, is a shaft 9 which rotatably supports a winding drum 10 having end flanges 11, 12. The flange 11 has bolted or otherwise securely fastened to it, a large spur gear 13; and the flange 12 has upon it an annular surface 14 for frictional engagement with a friction clutch device which will shortly be described.

The motor 5 has a driving pinion 15 which meshes with and drives a large spur gear 17 carried upon and keyed to a shaft 18, extending transversely of the skid 1 and journaled in bearings 19 and 20, respectively, mounted in the bracket or frame 2, 3. Near the bearing 20 the shaft 18 carries a pair of driving members, respectively a spur pinion 21 and a chain driving sprocket 22. The spur pinion 21 meshes with a spur gear 23, which is keyed to a third transverse shaft 24 journaled in bearings 25 and 26 in the bracket members 2 and 3. The shaft 24 has slidably connected therewith, but held against rotation with respect thereto, a bevel-toothed clutch member 27 pressed longitudinally of the shaft 24 by a spring 28. It will be understood that the clutch device 27 may be replaced by any other suitable apparatus for effecting a uni-directional driving connection between the shaft 24 and a spur pinion 29 which is rotatably mounted by means of a sleeve 30 near that end of the shaft 24 which is journaled in the bearing 25. The pinion 29 is formed upon the sleeve 30 which has suitable bevel teeth 31 adapted to cooperate with the bevel teeth 32 upon the clutch member 27. Clutch member 27 may be held by any suitable means against rotation relative to the shaft 24, and herein a sliding key connection 33 is shown,

for purposes of illustration. The spur pinion 29 meshes with and is adapted to drive the spur gear 13.

The chain sprocket 22 upon the shaft 18 is connected by a sprocket chain 35 with another, herein slightly larger, sprocket 36, which is rotatably mounted upon the shaft 9 by means of a sleeve portion 37, which carries at its end near the flange 12 a flange portion 38 provided, if desired, with a frictional pad 39 or the like, for engagement with the surface 14 of the drum flange 12. The flange 38 is constantly pressed toward the flange 12 by a spring 40 which is arranged between the end of the sleeve 37 and a threaded member 41 adjustably screwed upon the shaft 9, as at 42. Suitable casings 43 and 44 are provided for housing the gearing and chain drives.

The mode of operation of this apparatus will be readily understood and may be described in connection with the pulling of a prop. In Fig. 3 a prop P is shown connected by a rope 47 which extends around a suitably mounted guide sheave 48 to the drum 10 of the prop puller, which is arranged in an entry 49 where it will not be injured by falling of the roof upon the pulling of the prop P. By suitable manipulation of the controller, the motor 5 will be started; the pinion 16 will then drive the gear 17 and the shaft 18. Because a very heavy pull is necessary to release the prop, the sprocket 22 will rotate the sprocket 36 and with it the flange 38 and the friction member 39, but the power transmitted will be inadequate to cause rotation of the drum 10. However, the pinion 21 will be capable of rotating the gear 23 and thereby causing, through the clutch device 27, 30, the pinion 29 to drive the gear 13 and thereby effect rotation of the drum 10. There is a very large reduction in the two spur gear reduction stages 21, 23 and 29, 13; accordingly the prop will have its lower end released; and as soon as the prop is released there will be a great reduction in the amount of pull necessary to move it, a reduction which may be ten to one or more. Accordingly, the rotative force which the disc 38 and friction member 39 are adapted to transmit to the flange 12 will be sufficient to rotate the drum 10, and thereafter the driving train will change from the spur train 21, 23, 29, 13 to the chain and sprocket and friction clutch drive 22, 35, 36, 38, 39, 12. Of course, during the rapid rotation of the drum 10 the pinion 29 will be rotated much more rapidly than the shaft 24, but the bevel teeth 31, 32 and the spring support of the clutch member 27 will permit overrunning and very little loss of power.

From the foregoing description it will be apparent that I have provided an improved haulage mechanism adapted to provide a very heavy starting pull and then automatically to shift to a very much faster, though lighter, moving pull. It will be noted that the parts are simple and rugged, and in all respects suitable for use in mines or the like, where the best of care to operative mechanism is difficult to furnish.

While I have in this application specifically described one form which my invention may assume in practice, it will be understood that this form is shown for illustrative purposes only, and that the invention may be modified and embodied in various other forms without departing from its spirit or the scope of the appended claims.

What I claim as new and desire to secure by Letters Patent is:—

1. In a haulage mechanism, a winding drum, a motor, a plurality of driving trains between said motor and drum, and means including clutches in said drive trains responsive to variations in the winding effort to automatically render one of said trains ineffective and the other effective. 5

2. In a haulage mechanism, a motor, a drum, a train providing a large ratio of reduction, another train providing a small ratio of reduction, 10 said second mentioned train having a continuously loaded frictional driving connection with the drum, and means operative when said frictional driving connection is effective to permit overrun of the first mentioned drive train. 15

3. In a haulage mechanism, a motor, a drum, and a plurality of trains each having therein a spring loaded releasable drive connection structurally independent of the other and one yieldable at a load sustainable by the other whereby 20 one or the other is effective depending on the resistance to drum rotation.

4. In a haulage mechanism, a motor, a drum, and a plurality of sets of driving connections therefor each continuously tending to rotate said drum so long as said motor rotates, one set of said drive connections including a transmission device of a type which permits slippage only in one direction and the other including a transmission device of a type which permits slippage 30 in either direction upon overloading.

5. In a haulage mechanism, a motor, a drum, a plurality of sets of driving connections therefor each continuously tending to rotate said drum so long as said motor rotates, one of said 35 connections permitting overrunning upon rotation of the drum at a higher speed in a winding direction than the speed transmissible by said connection, and the other of said connections including provision for permitting slippage on 40 overloading.

6. In a haulage mechanism, a winding drum, a motor, a drive train between said motor and said drum including a constantly spring-loaded clutch permitting slippage between its parts in 45 either direction of relative rotation upon the existence of predetermined forces tending to effect such relative rotation, and a second drive train between said motor and said drum including a constantly spring-loaded clutch permitting over- 50 running.

7. In a haulage mechanism, a winding drum, a motor, a fast speed drive train for said drum driven by said motor and including a constantly loaded friction clutch coaxial with said drum, 55 and a slow speed drive train for said drum driven by said motor and including a constantly loaded overrunning clutch whose parts rotate on an axis parallel to a line parallel to the axis of the drum. 60

8. In a haulage mechanism, a winding drum, a motor, a fast speed drive train for said drum driven by said motor and including a constantly loaded friction clutch coaxial with said drum, and a slow speed drive train for said drum driven by said motor and including means for imparting a positive drive to said drum at a slower angular speed than that of the driving element of said friction clutch. 65

9. In a haulage mechanism, a winding drum, a motor, a fast speed drive train for said drum driven by said motor and including a constantly loaded friction clutch coaxial with said drum at one end of the latter, and a slow speed drive 70 75

train for said drum driven by said motor and arranged to impart a positive rotation to the opposite end of said drum.

10. In a haulage mechanism, a winding drum, a motor, a plurality of driving trains between said motor and drum each for driving the lat-

ter in the same direction and respectively transmitting rotative forces to the opposite ends of said drum, and means for automatically rendering one of said drives ineffective and the other effective.

ROBERT C. OSGOOD.
